(75) Inventor: **Jon Tyler Lundquist**, Chandler, AZ
(US)

(73) Assignee: **West Pharmaceutical Services, Inc.**,
Exton, PA (US)

(**) Term: **14 Years**

(21) Appl. No.: **29/402,109**

(22) Filed: **Sep. 21, 2011**

(51) **LOC (9) Cl.** **24-02**

(52) **U.S. Cl.**

USPC **D24/130**

(58) **Field of Classification Search**

Primary Examiner — David Muller

(74) *Attorney, Agent, or Firm* — Panitch Schwarze Belisario & Nadel LLP

(57) **CLAIM**

The ornamental design for a hub for medical container, as shown and described.

DESCRIPTION

FIG. 1 is a left-side perspective view of a hub for medical container in accordance with my new design;
FIG. 2 is a top perspective view thereof;
FIG. 3 is a left-side elevational view thereof;
FIG. 4 is a top plan view thereof; and,
FIG. 5 is a front elevational view thereof.

The features shown in broken lines depict environmental structure only and form no part of the claimed design.

1 Claim, 2 Drawing Sheets
